UNITED STATES PATENT OFFICE.

GUSTAV EGLOFF, OF CHICAGO, ILLINOIS, ASSIGNOR TO UNIVERSAL OIL PRODUCTS COMPANY, OF CHICAGO, ILLINOIS, A CORPORATION OF SOUTH DAKOTA.

PROCESS FOR CRACKING OIL.

Application filed October 31, 1921, Serial No. 511,714. Renewed March 12, 1926.

This invention relates to a process and apparatus for cracking oil and refers more particularly to a process and apparatus for converting petroleum hydrocarbons from relatively high boiling point oils to those having a low boiling point.

Among the salient objects of the invention are to provide a process in which the cracking is caused to take place in two successive zones and the vapors generated in each zone separately condensed; to provide a process in which relatively differential conditions of temperature and pressure are maintained in the respective zones whereby additional cracking is effected after the passing of the unvaporized portion from the first zone to the secondary zone of reaction; to provide a process in which the reflux condensate separated from the vapors in the two zones is returned and directed to the initial heating zone for retreatment.

The single figure is a side elevational view of the apparatus.

Referring in detail to the drawing, the oil to be treated is introduced from any convenient source from the inlet pipe 1 controlled by a valve 2 and is charged by means of the pump 3 through the charging line 4 into the heating coils 5 mounted in the furnace 6 which is preferably heated by means of gas burners 7. It is understood that the heating means may comprise a shell still or header type heating unit in place of the continuous coil as shown. The oil after being heated to a cracking temperature under a substantial pressure in the heating zone is passed through the transfer line 8 controlled by a valve 9 to the reacting or vaporizing chamber 10 where a greater part of the vaporization and cracking takes place. The generated vapors rise up through the dephlegmator 11 and after being refluxed pass out through the line 12 controlled by a valve 13 to the water condenser 14. Here the greater part of the vapors are reduced to liquid distillate, which is collected in the receiver 15 from which it may be withdrawn through the valve 16. The pressure on the initial zone of reaction may be controlled by means of a valve 18 in the pressure relief pipe in the top of the receiver. The unvaporized portion of the oil in the vaporizing chamber 10 is drawn off through the line 19 controlled by a valve 20 and is charged by means of the pump 21 to the secondary chamber 22 through

the line 23. This secondary chamber or zone of reaction is subjected to an increased temperature caused by the top fired furnace 24 positioned about the chamber 22 having the burner 24' positioned thereabove and provided with a stacking 25'.

In the secondary zone of reaction, the oil is subjected to increased temperature and pressure conditions as the unvaporized oil from the initial zone is somewhat more difficult to crack than when it is introduced to the initial heating zone. The heating of the oil by means of the top fired furnace prevents the overheating of the chamber or the forming of hot spots common to stills that are heated from beneath and particularly when the oil contained is of a residual character such as would be drawn off from the initial vaporizing chamber 10. In this secondary zone of reaction due to the increased temperature and pressure conditions, additional cracking is effected, the generated vapors rise from chamber 22 into the dephlegmator 25 and after being refluxed pass through the line 26 controlled by a valve 27 to the water condenser 28. The condensed distillate is collected in the receiver 29, and may be drawn off through the valve 30 as desired. The receiver 29 is equipped with a pressure relief valve 31 for controlling the pressure in the secondary zone of reaction. The chamber 22 is equipped with a residuum drawoff line 32 controlled by a valve 33. Reflux condensers 11 and 25 are equipped with reflux return lines 34 and 35 controlled by valves 36 and 37 respectively. These return lines communicate with a common connecting line 38 in which are interposed valves 39 and 40, whereby the reflux condensate from the separate reflux condensers can be returned in regulated quantities to the charging line 4, to be directed therethrough to the initial heating zone for retreatment.

By treating mid-continent gas oil in a process of this sort, a yield of from 40% to 50% of distillate ranging from 48 to 52 degs. Baumé may be produced. The temperature in the initial zone ranges from 700 to 800 degs. F. with a pressure maintained during operation of from 50 to 200 pounds while in the secondary zone, the temperature of the oil is raised in excess of 850 degrees and the pressure increased accordingly.

I claim as my invention:

1. A process for cracking hydrocarbon oil,

consisting in raising the oil to a cracking temperature under a substantial pressure in an initial stage of conversion, dephlegmating and condensing the generated vapors from 5 said stage, passing the unvaporized oil to a top fired secondary zone and there subjecting it to increased pressure and temperature conditions, dephlegmating and condensing the generated vapors relieved from the secondary 10 zone of reaction and collecting them separately from those produced in the initial stage.

2. A process for cracking hydrocarbon oil, consisting in raising the oil to a cracking temperature under a substantial pressure in an 15 initial stage of conversion, dephlegmating and condensing the generated vapors from said stage, passing the unvaporized oil to a top fired secondary zone and there subjecting it to increased pressure and temperature conditions, dephlegmating and condensing the generated vapors relieved from the secondary 20 zone of reaction and collecting them separately from those produced in the initial

stage, and returning the reflux condensates 25 from the respective zones to the initial cracking zone for retreatment.

3. A process for cracking hydrocarbon oil, comprising maintaining a body of oil under given cracking conditions of temperature 30 and pressure in an enlarged zone, taking off vapors from said enlarged zone, passing unvaporized oil from said enlarged zone to a second enlarged zone, wherein further cracking of such unvaporized oil is effected under increased temperature and pressure conditions, applying the maximum heat to that portion of said second enlarged zone occupied by vapors, removing vapors from said second enlarged zone, subjecting vapors removed from each of said enlarged zones to reflux condensation, uniting the reflux condensate separated therefrom, again subjecting such reflux condensate to a cracking temperature, and thereafter uniting the same 40 with the oil in said first enlarged zone. 45

GUSTAV EGLOFF.
